INVENTOR.

BY *Henry H. Burns*
Raymond A. Parker
ATTORNEY.

UNITED STATES PATENT OFFICE.

HENRY H. BURNS, OF BATTLE CREEK, MICHIGAN.

LIFTING JACK.

Application filed September 28, 1921. Serial No. 503,719.

To all whom it may concern:

Be it known that I, HENRY H. BURNS, citizen of the United States, residing at Battle Creek, county of Calhoun, State of Michigan, have invented a certain new and useful Improvement in Lifting Jacks, and declare the following to be a full, clear, and exact description of the same, such as will enable others skilled in the art to which it pertains to make and use the same, reference being had to the accompanying drawings, which form a part of this specification.

My invention relates to lifting jacks and an object of my improvements is to provide a jack primarily for raising the axle of an automobile and having an improved construction and mode of operation.

I accomplish this object in the apparatus shown in the accompanying drawings, in which:—

Figure 1 is a side elevation of a jack embodying my invention.

Fig. 2 is a section on the line II—II of Fig. 1.

Fig. 3 is a detail section on the line III—III of Fig. 1.

Fig. 4 is a side elevation looking at the opposite side to that shown in Fig. 1, the upper end of the lifter rod being broken away and a part being broken away to more plainly show a detail of construction.

Fig. 5 is a section on the line V—V, Fig. 1, the upper end of the lifter rod being broken away.

Fig. 6 is a section on the line VI—VI, Fig. 4, some of the parts being partly broken away.

Fig. 7 is a detail view partly in section showing a modified construction of the lever supporting link.

a indicates the base or pedestal of the jack; this is made up of two supplementary stampings from sheet metal *aa*, *ay*. Each of these parts consists of a flat portion to rest upon the ground, having vertical flanges *a²* and *a³* with a half socket portion *a⁴* between these flanges. The two parts are united by rivets *a⁷*, *a⁸* passing through the flanges *a²* and *a³*. The material of which the pedestal is composed is cut and bent inward at *a⁵*, *a⁶* (Fig. 5) to form lugs extending into the socket *a⁴*.

b is a length of channel iron of a shape

and cross-section corresponding to the interior of the socket *a⁴*. This is placed in said socket, its lower edge resting upon a flange *a⁵*.

c is a strip of metal adapted to fit over and close the otherwise open portion between the side flanges of the channel iron *b*, its lower edge resting upon a lug *a⁵* opposite to that upon which the web of the channel iron rests. *a⁶* is a rivet passing transversely through the walls of the socket *a⁴*, through the web of the channel iron *b* and through the lower end of the plate *c*, thus firmly holding the channel iron and plate in position and assisting to bind the two halves of the base together.

d is a strip of band iron passing around the upper ends of the channel iron *b* and plate *c* and having its ends held together by the rivet *d²*. The band *d* serves to secure the upper ends of said channel iron and plate firmly together in their relative positions. The ends of the band *d* are turned outward parallel to each other and form a securing lug hereinafter referred to.

b² is a slot formed through the web of the channel iron *b* centrally thereof and *c²* is a corresponding slot through the plate *c* opposite the slot *b²*.

e is a lifter-rod, or plunger, fitting and adapted to reciprocate within the tubular construction formed by the channel iron *d* and plate *c*. The lifter rod *e* is provided with a bracket *f* at its upper end having seats *f²*, *f³* at different levels upon which the axle engages.

e² indicates apertures formed transversely through the bar *e* opposite the slots *b²* and *c²*.

g is a metal strip pivoted at one end to the lug extending from the strap iron *d*. *g²* is a second strip of metal also pivoted to the lug extending from the strip *d* and extending downward bending toward the strap *g* and being secured thereto towards its outer end. The metal strip *g²* at its outer end is bent outward and backward to form the hook *g³*. *g⁴* is a rivet passing through the outer ends of the metal strips *g* and *g²* and through the backwardly turned portion of the latter strip.

h is a dog or pawl pivoted at one end to the lug extending from the strip *d* and being provided with a guide piece *h³* at its outer end.

g^1 is a pivot pin extending through the lug from the strap d and serving as a support for the pivoted parts g , g^2 and h .

The metal strips g and g^2 form a support link for the lever arm j , hereinafter described.

j is a lever arm rectangular in cross-section and twisted at one end into shape to form the pedal j^3 . j^2 is a cylindrical pin extending laterally from the end of the lever arm j opposite to that formed into the pedal j^3 . The pin j^2 is of a size and shape to fit within the apertures e^2 formed through the lifter rod e . j^5 indicates semicircular grooves formed in the lower edge of the lever arm j at a suitable position to engage the intermediate portion of the rivet g^4 , as hereinafter described. j^4 is a notch cut in the upper edge of the lever arm j at the proper position.

k is a lever pivoted at k^3 to the side of the lever arm j and adapted to oscillate in the plane of said arm. One end of the lever k extends to a position below the slot j^4 ; the other end extends to a position adjacent the pedal j^3 . k^4 , k^5 indicate pins upon the side of the lever arm j adapted to limit the oscillating movement of the lever arm j . The lever arm j is adjusted to position by placing its pin j^2 within an aperture e^2 , said pin extending through the slot c^2 and by a lateral movement coming within the upturned portion g^3 of the link g , a notch j^5 engaging over the rivet g^4 within the upturned portion of said link. The pawl or dog h now engages with its guide the part h^2 over the upper edge of the lever arm j in such a position that when the pedal portion j^3 of the said lever arm is depressed to the limit of its travel, the lower end of the dog h shall engage in the notch j^4 and hold said lever in the position to which it has been adjusted.

The lever arm j may be adjusted to position by a lateral and downward motion with the form of suspension link shown in the first six figures of the drawings. If a stronger suspending link is required, the form shown as a modification in Fig. 7 may be used, in which a piece of strap iron g^{2a} is substituted for the iron g^2 and forms with the strip g an angular loop into which the lever arm j must be inserted by an endwise motion.

The operation of the above-described device is as follows:

The jack is placed under the axle to be lifted and the lifter bar e is raised until the axle engages upon a seat f^2 or f^3 . The lever arm j is then placed into the position with its pin j^2 engaging through an aperture e^2 , one of the slots j^4 engaging the pin g^4 in the stirrup g , g^2 and the pedal j^3 being in an elevated position. The pawl h now rests upon the smooth upper edge of the lever arm j . The operator places his foot upon the pedal j^3 and presses it downward, thus

oscillating the lever arm j about the pivot pin j^4 and forcing the lifter bar e upward raising the axle. When the pedal has been pressed down to one limit of its travel, the dog or pawl h engages in the notch h^4 and holds the lever arm j in its adjusted position, thus automatically fastening the lifting bar in its position with the axle raised. When it is desired to lower the axle the operator again places his foot upon the pedal j^3 and turns it to press downward on the adjacent end k^2 of the lever k . This oscillates the lever k about its pivot k^3 causing the other end of said lever to engage a part of the guard piece h^2 and press the dog h out of engagement with the slot j^4 . This disengages the lever arm j and the operator permits the pedal j^3 to raise thus allowing the lifter bar e to descend and lowering the axle.

What I claim is:

1. In an apparatus of the kind described, the combination of the supporting guide b , a band d engaging around the upper end of said guide and provided with an outwardly extending lug, a link g pivoted to said lug and depending therefrom, a lifting bar adapted to reciprocate in said guide, a lever j pivotally supported upon said link and engaging said lifting bar to actuate the same, said lever being provided with a notch at its upper end, a pawl h pivoted to said lug at one end and at the other end resting upon said lever so as to engage in said notch.

2. In an apparatus of the kind described, a reciprocating lifting bar, a guide for said bar, said guide leaving one side of said bar exposed, transverse apertures extending into said bar from the exposed side thereof, a swinging link pivoted at one end to said guide, and a lever adapted to actuate said bar, said lever being adapted to engage in the apertures in said bar by a lateral motion, said lever being adapted to pivotally engage said swinging link by the same lateral movement.

3. In an apparatus of the kind described, a vertical guide b , a lifting bar adapted to reciprocate in said guide, said guide being so constructed as to leave one side of said reciprocating bar exposed, apertures extending into said bar from the exposed side thereof, a swinging link pivoted to said guide at one end and provided with a pin toward the other end, a lever j having a laterally extending pin j^2 adapted to engage in said apertures, said lever being adapted to pivotally engage the pin on said link when in position to cause the pin j^2 to engage in one of said apertures.

4. In an apparatus of the kind described, a vertical guide b , a lifting bar adapted to reciprocate in said guide, said guide being so constructed as to leave one side of the reciprocating bar exposed, apertures extending into said bar from the exposed side

thereof, a lever *j* having a lateral extending pin *j*² adapted to engage in said apertures by a lateral movement, a fulcrum supported by said guide, said lever being adapted to engage said fulcrum when in position to cause the pin *j*² to engage in one of said apertures.

5. In an apparatus of the kind described, a vertical guide *b*, a lifting bar adapted to reciprocate in said guide, said guide being so constructed as to leave one side of said reciprocating bar exposed, apertures extending into said bar from the exposed side thereof, a lever *j* having a laterally extending pin *j*² adapted to engage in said apertures by a lateral movement, a fulcrum supported by said guide, said lever being adapted to engage said fulcrum and said fulcrum

being adapted to permit the movement of said lever to engage and disengage said pin. 20

6. In an apparatus of the kind described, the combination of a lifting bar and a channel iron, said lifting bar engaging within said channel iron and reciprocating therein, a plate extending between the outer edges 25 of the side flanges of said channel bar and secured in place to retain said bar in position, and a sheet iron base having the lugs *a*⁵ turned inward from the material thereof, said base binding said plate and channel iron together and said lugs supporting said channel iron and plate. 30

In testimony whereof, I sign this specification.

HENRY H. BURNS.
